UNITED STATES PATENT OFFICE.

ROBERT HARRISON AUSTIN, OF SAN FRANCISCO, CALIFORNIA.

JAR-CLOSURE.

SPECIFICATION forming part of Letters Patent No. 691,696, dated January 21, 1902.

Application filed May 16, 1901. Serial No. 60,567. (No model.)

To all whom it may concern:

Be it known that I, ROBERT HARRISON AUSTIN, a citizen of the United States, residing at San Francisco, in the county of San Francisco and State of California, have invented a new and useful Jar-Closure, of which the following is a specification.

My invention is an improvement in jar-closures, and has for its object to provide a simple, cheap, yet effective device for locking the top of a jar in position.

The object of my invention is to provide a device that can be quickly and easily attached or detached to or from a jar and when in position will firmly clamp the top, so that air or moisture will be excluded from the jar.

With the above object in view my invention consists in certain new combinations and arrangements of parts, as will be fully described in the following specification and pointed out in the appended claims, reference being had to the accompanying drawings, in which—

Figure 1 is a perspective view of the upper portion of a jar with my improvements applied. Fig. 2 is an enlarged section on the line 2 2 of Fig. 1. Fig. 3 is a plan view. Fig. 4 is a detail view illustrating the manner of securing the levers to the base. Fig. 5 is a detail view of a portion of the frame. Fig. 6 is a detail view of one of the clamping-arms. Fig. 7 is a detail horizontal section on the line 7 7 of Fig. 2, and Fig. 8 is a detail section on the line 8 8 of Fig. 7.

In the drawings, A designates the jar, which is of the conventional shape, having a flange a near the upper end, upon which is placed the usual packing-ring, upon which the flange of the top B rests. The lower face of the flange is undercut or inclined upwardly, as shown at a' and as most clearly shown in Fig. 2.

My improvement is so constructed that it can be applied to the jars now generally used and consists of a base C, having four arms c diverging from the center thereof, which extend nearly to the edge of the top B, and having their upper surfaces beveled, as shown at c'. At a point adjacent the beveled ends the arms are provided with pins c², which are formed integral with the said arms and whose ends are bent over toward the sides of the

arms, the purpose of which will appear later on.

D designates a series of levers or arms, one 55 being arranged in position upon each of the arms of the base and having an aperture d near their outer ends, through which is passed the pins c², that retain the levers in place. These openings are elongated at the upper 60 portion of the levers, said elongations running the length of the levers, as clearly shown and for the purpose as will also appear later on. The extreme outer ends of the levers are provided with apertures d', through which are 65 passed the shanks of clamping members E, which are bent over at the ends, forming eyes f, that encircle the ends of the levers and by which the said members are retained in place. The lower ends of the clamps are provided 70 with foot portions f', whose upper surface is beveled or inclined to fit under the flange, and in order to adjust the foot portions in place without entirely unfastening the screws H, I provide the flange with cut-out portions 75 a² to receive the inclined foot-sections, as will be described later on.

In order to adjust the clamps, I provide the inner ends of the lever D with apertures d², that receive the ends g of a clamping-plate 80 G, whose center is provided with an aperture through which is passed the shank of a clamping-screw H, which enters a screw-threaded aperture in the center of the base-plate C. In practice I prefer to bend the ends g of the 85 clamping-plate to encircle the ends of the levers, which prevents any accidental displacement or loss of the several parts.

The operation of my improvement is as follows: After the top has been placed on the jar my improved clamp is arranged in position so that the clamping members properly hang down the sides of the jar, the foot portions registering with the cut-out sections in the flange. The top is then given about one-quarter turn, so that the clamps will rest between the said cut-out sections. Then by turning the screw the inner ends of the levers are drawn down and the outer ends correspondingly raised, which draws the clamps up under the flange and tightly clamps the top in place. 95 100

It will thus be seen that I provide a simple arrangement of parts that can be quickly and

easily adjusted, and by making the upper surface of the foot portions of the clamps beveled to fit a correspondingly-shaped flange all possible danger of the clamps slipping is avoided.

By providing the bevel surface at the outer ends of the arms I obtain a fulcrum for the lever at the juncture of the bevel and the flat horizontal surface of the arms, and to prevent the arms being disengaged the pins are bent at right angles to the body portion thereof. Now to position the levers on the arms of the base the former are turned crosswise to the length of the arms on an angle, as shown in dotted lines in Fig. 4. The pins being inserted in the apertures, the arms are then brought to a horizontal position, as shown in full lines in said figure, when they are swung around to their operative position. This operation I am enabled to obtain by making the upper end of the aperture elongated, which permits the passage of the angle portion of the pins, as will be readily understood.

Having thus fully described my invention, what I claim as new, and desire to secure by Letters Patent of the United States, is—

1. A jar-closure comprising a base-section having arms diverging from the center thereof, levers pivotally held upon the said arms, clamping-sections having their lower or foot portions arranged for engagement with the flange of a jar, a clamping-plate connected to the inner ends of the said lever, and a screw

connecting said plate to the base, substantially as shown and described.

2. A jar-closure comprising a base-section having arms diverging from the center thereof, and having the outer ends beveled upon the upper side, pins formed integral with the said arms, levers provided with apertures for engagement with said pins and having their extreme ends also provided with apertures, clamping members connected to the outer ends of said levers, a clamping-plate for engagement with the inner ends of said levers, and means for adjustably connecting said clamping-plate and base, substantially as shown and described.

3. In a jar-closure, the combination of a base-section having arms diverging from the center thereof, the outer ends of the said arms being beveled upon the upper side, retaining pins formed on the said arms and having their upper ends bent at right angles to the body of said pins, levers having apertures for engagement with said pins, clamping-sections loosely held upon the outer ends of said levers and having the upper surface of their foot portions beveled, a clamping-plate connected to the inner ends of said levers, and means for connecting said plate and base-section, substantially as shown and described.
